FORCED AIR WALL HEATER

Paul D. Kilbury, Hawthorne, Calif.

Application March 22, 1954, Serial No. 417,630

2 Claims. (Cl. 126—110)

The present invention relates generally to space heaters, and is more particularly concerned with space heaters of the forced air type which are adapted for mounting in the wall of a room or building.

One object of the herein described invention is to provide a wall heater in which a portion of the air is supplied to a heating chamber by means of a blower, while a portion of the air which is supplied to the heating chamber is provided for by inducing additional air flow at the blower discharge by the action of the air discharge from the blower. In this way, load on the motor driving the blower is reduced and more quiet operation is obtained.

Another object of the invention is to provide in a wall heater a casing and heating chamber having outer walls in spaced relation so as to provide an air passage through which air is circulated during operation of the heater. The casing of the heater is thus maintained cool during operation, and the plaster and wall structure may be carried into contact relation with the casing.

Further objects of the invention will be brought out in the following part of the specification, wherein detailed description is for the purpose of fully disclosing the invention without placing limitations thereon.

Referring to the accompanying drawings, which are for illustrative purposes only:

Fig. 1 is a front elevational view of a wall heater embodying the features of the herein described invention, portions being cut away and shown in section to disclose the operative relationship of certain of the heater parts;

Fig. 2 is a vertical section through the heater of Fig. 1, taken substantially on line 2—2 of Fig. 1; and

Fig. 3 is an enlarged detailed sectional view at the blower outlet, taken substantially on line 3—3 of Fig. 1.

Referring more specifically to the drawings, the wall heater of the present invention is enclosed within a rectangular upright casing 10 in which a forward wall 11 is provided with an upper or top opening 12 and a lower or bottom opening 13. The opening 12 is shown as being covered with a conventional grille 14, while the bottom opening is covered with a grille 15. These grilles may be of conventional construction and are shown as being arranged with peripheral edge portions to facilitate securement in operative position and ready removal when required to permit access to various parts of the heater. The casing is constructed with a back wall 16 which is connected with the front wall 11 by side walls 17 and 18.

Within the casing 10, there is further provided a box like structure having a forward wall 19, a back wall 20, and side walls 21 and 22 which cooperate to form a heating chamber 23. It will be observed that the associated walls of the casing and the box like structure are in spaced relation so as to form an air flow passage therebetween for cooling purposes and to maintain the casing wall in a cool condition during heater operation. With such cooling, the wall and plaster structure of the room or building may be carried up to and directly into contact with the heater casing.

2

The lowermost end of the heating chamber 23 is closed by a wall member 24 which acts as a partition to separate the casing into an upper compartment containing the heating chamber, and a lower compartment 25. The 5 heating chamber communicates through an opening 26 in its front wall with a portion of the casing opening 13, while the lower compartment 25 communicates through an opening 27 with another portion of the casing opening 13. Moreover, as shown in Fig. 2, a filler guide plate 10 28 is mounted in the lower corner angle formed by the back wall 20 and partition 24 so as to provide a more uniform flow path for air from the heating chamber to the opening 26.

At its uppermost end, the heating chamber has a wall 15 29 provided with a central inlet opening 30 over which there is mounted a plate member 31 of generally rectangular construction, this plate being supported in spaced relation by spacer elements 32 and secured by bolts 33 at its corners.

The plate 31 has a blower 34 mounted thereon, the blower having a casing scroll 35 with its outlet neck 36 connected to the plate 31 and arranged to discharge air through an appropriate opening in the plate. Intake air enters the blower casing through an opening 37 positioned on the opposite side of the casing from a blower driving motor 38. With the blower thus arranged, intake air is drawn in through the grille 14 and discharged into the heating chamber where its entrance is distributed by means of deflectors 39, 40 and 41.

Movement of the air discharge from the blower 34, as it passes through the space below plate 31 and into opening 30, acts to induce an additional flow of air to the extent of 30% to 40% into the heating chamber. The load on the blower is thus relieved, with the result that the blower operates more quietly than if all the air were taken through the blower.

A main duct passage, as indicated by the numeral 42, is provided for conducting hot gases of combustion through the heating chamber 23 into heat exchange relation with the air forced therethrough by the action of the blower 34.

The main duct passage includes a relatively flat box-like walled hollow structure of substantially rectangular configuration, which forms a combustion chamber 43. This combustion chamber is positioned adjacent the forward wall 19 of the heating chamber 23, and at its lowermost end is connected through a plurality of tubular inlet ducts 43' in spaced apart relation, these ducts having their lowermost ends anchored in the wall member 24 and in communication with the lower compartment 25.

At the uppermost end of the combustion chamber, a plurality of outlets 44 are arranged to conduct the hot gases of combustion from the combustion chamber 43 into a radiator 45 of hollow construction, this radiator being supported on the rear side of the combustion chamber and having walls of similar construction to that of the combustion chamber in that these walls may be fluted or otherwise fabricated to increase the heat transfer therethrough.

The interior of the radiator 45 is sectionalized by a partition 46 to the end that the gases of combustion will initially move through a pass 47 in a downward direction to the bottom of the radiator and thence in an upward direction through a pass 48 to an outlet connection 49 at the top of the heating chamber 23.

It is a feature of the invention to mount a fuel burner 50 directly within the combustion chamber. The burner 50 comprises generally an elongate body portion 51 which carries on its upper surface a plurality of burner nozzles 52, these nozzles being fed with fuel, in this case a gas, through a venturi supply tube 53 of reverse channel construction, and formed at its entrance end with an inlet 54

for primary air. A pipe connection 55 supplies gas fuel to the burner for mixing with the primary air in the venturi which acts to provide a thoroughly mixed combustible mixture and uniformly deliver it to the nozzles 52.

By placing the fuel burner 50 directly in the combustion chamber, air for combustion provides the secondary air supply. The air for combustion enters the inlet ducts 43', and since these ducts are in the path of flow of heated air discharged from the heating chamber through the upper portion of the grille 15, it will be apparent that the entering air will be initially preheated in its flow to the burner, thus increasing the efficiency of the heater. The air for combustion is supplied to the inlet ducts 43' from the lower compartment 25, the air entering this compartment through the lower portion of the grille 15.

A flue connection 55 is provided at the upper end of the casing 10. This flue connection at its innermost end communicates with a vent diverter of conventional construction, and shown as comprising a box 56 having a longitudinally extending upstanding partition 57 therein. This partition separates the box into compartments 58 and 59 which are interconnected at their upper ends through a space or opening 60 lying above the partition 57.

The lower end of the compartment 58 is provided with a nipple 61 which connects with outlet connection 49. The upper end of compartment 59 connects with the flue 55 while the lower end of this compartment is in communication with a flared inlet duct 63 which is positioned with its inlet opening covering a portion of the grille 14. The operation of the vent diverter in heaters of this type is well known and in general the diverter prevents variations in draft conditions in the flue from being reflected into the combustion chamber where it could influence the operation of the burner. Vent diverters are a conventional safety feature which has been incorporated into the heater of the present invention.

From the foregoing description, it will be apparent that the wall heater embodying the features of the present invention operates in a different manner than conventional heaters of this type in that it takes air from or adjacent to the ceiling and, after passing it through a heating chamber, discharges the heated air at or near floor level where it replaces cold air and provides warmth where needed. By circulating the heated air in this manner, the usual effects of stratification are avoided and a more healthful condition provided.

Various modifications may suggest themselves to those skilled in the art without departing from the spirit of my invention, and, hence, I do not wish to be restricted to the specific form shown or uses mentioned, except to the extent indicated in the appended claims.

I claim:

1. A space heater, comprising: an upright casing having side walls; partition means separating said casing into upper and lower compartments, the upper compartment having an air inlet at its upper end and an air outlet at its lower end, and the lower compartment having an air inlet; means including side walls and a top wall having an opening therein providing a heating chamber in the upper compartment of said casing, said top wall being disposed below the upper end of said casing to provide a space above said heating chamber, said chamber having its lowermost end in communication with said air outlet, and said casing and said heating chamber having their side walls spaced so as to form a passage around said heating chamber communicating at its upper end with the space above said top wall, the lower ends of the side walls of said heating chamber cooperating with said partition means to form a communication of said passage with said lower compartment for upward flow of air therefrom;

means providing a combustion chamber in said heating chamber connected to receive combustion air from said lower compartment; a burner in said combustion chamber; vent means communicating with said combustion chamber; and air moving means in the space above said top wall in said upper compartment having an inlet positioned to receive air from the air inlet in the upper end of said upper compartment, said air moving means having an outlet directed toward and spaced from the opening in said top wall for discharging an air stream into the opening for flow through the heating chamber and discharge through said outlet into a space to be heated thereby whereby additional flow of air is induced through said opening into the air stream from the lower compartment and through the space between the side walls of the heating chamber and casing to cool the same.

2. A space heater, comprising: an upright casing having side walls; partition means separating said casing into upper and lower compartments, the upper compartment having an air inlet at its upper end and an air outlet at its lower end, and the lower compartment having an air inlet; means including side walls and a top wall having an opening therein providing a heating chamber in the upper compartment of said casing, said top wall being disposed below the upper end of said casing to provide a space above said heating chamber, said chamber having its lowermost end in communication with said air outlet, and said casing and said heating chamber having their side walls spaced so as to form a passage around said heating chamber communicating at its upper end with the space above said top wall, the lower ends of the side walls of said heating chamber cooperating with said partition means to form a communication of said passage with said lower compartment for upward flow of air therefrom; an upright combustion chamber in said heating chamber connected to receive combustion air from said lower compartment and having an outlet in its upper portion for hot gases of combustion; a burner positioned within the lower portion of said combustion chamber; a radiator adjacent said combustion chamber extending generally downwardly from the upper end of the combustion chamber and being connected at its upper portion with the combustion chamber outlet; deflector means positioned in said heating chamber above said combustion chamber and radiator to distribute air flowing downwardly through said heating chamber; vent means connected at the upper end of said radiator; and air moving means in the space above said top wall in said upper compartment having an inlet positioned to receive air from the air inlet in the upper end of said upper compartment, said air moving means having an outlet directed toward and spaced from the opening in said top wall for discharging an air stream into the opening for flow through the heating chamber and discharge through said outlet into a space to be heated thereby whereby additional flow of air is induced through said opening into the air stream from the lower compartment and through the space between the side walls of the heating chamber and casing to cool the same.
